UNITED STATES PATENT OFFICE

2,582,002

RAILWAY CAR

James E. Candlin, Jr., Chicago, Ill., assignor to
Pullman-Standard Car Manufacturing Company,
Chicago, Ill., a corporation of Delaware

Application August 2, 1945, Serial No. 608,502

4 Claims. (Cl. 105—344)

1

Travel by present day de luxe railroad coaches is exceedingly popular, and this popularity has grown to such an extent that there are in use many trains made up entirely of day coaches of the so-called de luxe type. These coaches are intended for both day and night use.

One explanation for this popularity is the low cost to the passenger in comparison with other classes of railroad travel. This is made possible because of the large number of passengers that can be accommodated in each car. In determining the cost of travel for each passenger, the amount of space utilized by a passenger is, of course, the primary consideration. Additional comfort in a railroad car in most instances can be provided only at the expense of revenue earning space, resulting, of course, in increased cost of travel to the passenger benefiting by the additional space.

The present invention adds considerably to the comforts of coach passengers without materially reducing the revenue earning space by affording more of the conveniences normally supplied only to those travellers who pay higher fares. An object of the invention is to adapt the day coach more nearly to the essential requirements of passengers travelling both at daytime and at nighttime. This is done by supplying additional toilet facilities both for men and women during the morning hours when such facilities are in maximum demand without necessitating the setting aside of this additional available floor space as a complete financial loss to the railroad. In other words, the space required for these additional facilities must necessarily be taken from the floor area that in conventional equipment is utilized to earn revenue for the railroad. It is only during those hours when additional toilet facilities are required that this space need be thus used, and during the remaining hours of the daytime and nighttime, at least most of this space can be utilized for earning revenue for the railroad.

The present invention supplies this need in a unique manner without utilizing more than a minimum amount of floor space for non-revenue earning accommodations. In making this possible, a unique washbasin arrangement is provided, and its relationship to the seats is such that additional seating accommodations are available at all times when the basins are not needed.

Some of the objects and advantages of the invention are evident from the foregoing while others will become apparent from the following description and the drawings, in which:

Fig. 1 is a diagrammatic plan view of a railway passenger car with a portion broken away and showing one embodiment of the invention and its relationship to the remainder of the car;

Fig. 2 is a view corresponding to Fig. 1 but showing a second embodiment of the invention;

Fig. 3 is an enlarged diagrammatic plan view of the basin unit shown in Fig. 1;

Fig. 4 is an enlarged fragmentary vertical sectional view shown partially in elevation and taken on the line 4—4 of Fig. 3;

Fig. 5 is a sectional view taken on the line 5—5 of Fig. 4;

Fig. 6 is a front elevational view of the basin unit shown in Fig. 4 and illustrating the relationship between the basin unit and the seats disposed therebeneath;

Fig. 7 is a fragmentary transverse sectional view taken through the lounge shown in Fig. 1 showing the basin unit in operative position with the seats therebeneath illustrated in inoperative position;

Fig. 8 is a vertical transverse sectional view corresponding to Fig. 7 but showing the basin unit in its inoperative position with the adjoining seats in operative position;

Fig. 9 is an enlarged, fragmentary, vertical sectional view corresponding with Fig. 4, but showing another embodiment of the present invention;

Fig. 10 is an enlarged fragmentary sectional view through the back rest, basin unit, with a portion of the mechanism being shown in elevation, the view being taken on the line 10—10 of Fig. 9;

Fig. 11 is a diagrammatic view of the locking mechanism for the back rest, basin unit;

Fig. 12 is an enlarged vertical sectional view taken on the line 12—12 of Fig. 11;

Fig. 13 is an enlarged, fragmentary, longitudinal sectional view at one end of the locking mechanism shown in Fig. 11 and showing more or less in detail the arrangement for one of the locking bolts;

Fig. 14 is a transverse sectional view through the locking mechanism taken on the line 14—14 of Fig. 13; and

Fig. 15 is a fragmentary vertical sectional view through the stop, the view being taken on the line 15—15 of Fig. 9.

For purposes of illustration, specific embodiments of the invention have been selected in compliance with Sec. 4888 of the Revised Statutes, but it is recognized that modifications may be made without departing from the intended scope of the invention.

Referring now to Fig. 1, the invention is illustrated in conjunction with a railway car generally indicated at 25 comprising a pair of side walls 26 and 27 and end walls 28 and 29, extending beyond which end walls are vestibules 30.

In the car interior throughout most of its length are seats 31 arranged in pairs along the side walls of the car, and an aisle extends lengthwise along the center of the car.

As shown in Fig. 1, adjacent to car end wall 28 is a lounge generally indicated at 32 disposed adjacent to car side wall 27, and it is bounded on one side by this car side wall and on the other three sides by walls comprising an aisle wall 33 and a pair of end walls 34 and 35. Aisle wall 33 is spaced from car side wall 26 to provide an aisle 36 adjacent to car side wall 26 and is connected with the center aisle. The car may include the usual equipment locker 37 and a drinking fountain 38.

Between the lounge end wall 35 and the car end wall 28 is a toilet 39 provided with a door 40 giving access to aisle 36 and a second door 41 leading into the lounge 32. At the opposite end of the lounge 32 adjacent to wall 34 are two toilets 42 and 43 provided with doors 44 and 45, respectively, leading into lounge 32. The toilet 42 is further provided with a door 46 leading to the aisle 36. Toilets 39 and 42 may be provided each with a washbasin 47 and a hopper 48 while toilet 43 may be provided only with a hopper 49.

In the form of the invention shown in Fig. 1, a pair of doors 55 and 56 are disposed in the aisle wall 33 to provide access from aisle 36 into the lounge 32. As shown, these doors 55 and 56 are centrally located with respect to the aisle wall 33 and a folding partition 57, secured to the aisle wall 33 at a position between doors 55 and 56, divides the lounge 32 into two rooms 32a and 32b. This partition 57 when closed joins the side wall at 58. Door 55 provides access to room 32a, and door 56 provides access to room 32b. When open, partition 57 assumes a position against door 55 so as to leave accessible only door 56 leading from the aisle directly into the lounge.

Each of the rooms 32a and 32b is provided with seating means—for example, individual chairs 60—disposed with their backs against the car side wall 27, and a convertible unit, generally indicated at 61, that comprises a washbasin unit 62 and seating means 63. The basin unit 62 can be moved from the operative position shown, for example, in room 32b, where it covers and makes inaccessible the seats therebelow, to an inoperative position against aisle wall 33, as shown in room 32a, in which position the seats 63 are made accessible for use. As shown in Fig. 1, seats 63 are individual chairs provided with backs that are collapsible, as will be brought out hereinafter. In Fig. 2, the seating means is in the form of a couch 164 provided with space for three persons.

Each of the rooms 32a and 32b may be further provided with a dental lavatory 65 and a drinking cup dispenser 66.

Referring now to Fig. 3, the basin unit 62 comprises an elongated housing 70 provided with three washbasins 71, 72, and 73 spaced lengthwise in the housing 70 and disposed adjacent to the housing front wall 74. This housing 70 is further provided with a back wall 75, a bottom wall 76, and a top wall 77, all of which walls, together with end walls 78 and 79, form a rectangular box-like enclosure. In the region of each basin, the top wall 77 extends from the back

wall 75 only part way toward the front wall 74, leaving an opening for the basins 71, 72, and 73. Each of the basins 71, 72, and 73 is provided with a flange 80 along its forward edge that projects forwardly and downwardly at 85 to form part of the front wall 74. Bottom wall 76 of housing 70 overlaps this projecting portion at 81. A flange 86 on the free edge of basin projection 85 serves as a means for fastening these walls together. Along the back of the basin 72 is a horizontal projection 82 provided at its free end with an upstanding flange 83. An angle member 84 serves to fasten the upstanding flange 83 to the top wall 77 of housing 70.

As best shown in Fig. 4, a cover member generally indicated at 87, is hinged at 88 to the top wall 77 of housing 70 and extends over the basins 71, 72, and 73. This cover member 87 is provided with a downwardly extending box-like container 89 at its outer end that projects downwardly along the front wall 74 of the box-like housing 70. This container includes for each basin a towel container 89a and a used razor blade container 89b (see Fig. 3). The cover member 87, hinged as it is at 88, may be rotated to an open position indicated in broken lines at 87a in Fig. 4, in which position the washbasins 71, 72, and 73 are made accessible. The box-like container 89 is hollow and, as indicated, for example, in Fig. 6, is provided with a plurality of slots 90, one of which is disposed adjacent to each of the washbasins 71, 72, and 73. These slots 90 provide access into the interior of the member 89a so that fresh towels and the like may be housed inside of member 89 and can be obtained through opening 90. Member 89 may further be provided with smaller slots 91 through which used razor blades may be deposited and held inside the housing member 89b. A lid 92, hinged at 93, may be provided on the member 89 so that the used razor blade container may be emptied.

Referring to Fig. 3, the housing 70 is mounted between spaced, box-like side members 94 and 95, and is hingedly mounted on these members in a manner shown in Figs. 4 and 5. The hinging arrangement on both sides of the housing 70 comprises a pair of cooperating hinge members 96 and 97, one of which is mounted on the housing 70 and the other on the adjacent end member 94 or 95. As shown in Figs. 4 and 5, the hinge member 96 is provided with a pair of arcuate tracks or slots 98 and 99 adapted to receive cooperating lugs 100 and 101, respectively, projecting outwardly from and forming part of the hinge member 97. Lug 100 is adapted to ride in slot 98, whereas lug 101 rides in slot 99. The curvature of slot 98 is about the lower end of slot 99 as its center, whereas the curvature of slot 99 is about the right-hand end of slot 98, as shown in Fig. 4.

Thus, when the basin unit 62 is in its horizontal position, shown, for example, in room 32b, and also shown in solid lines in Fig. 4, lug 100 is disposed at the left-hand end of slot 98, whereas lug 101 is disposed in the lower right-hand end of slot 99. As the basin 62 is swung downwardly in a clockwise direction, during the first part of its movement the lug 100 moves from the position shown in Fig. 4 to the right-hand end of slot 98, revolving about lug 101 disposed at the lower right-hand extremity of slot 99, during which movement the basin 62 moves somewhat away from aisle wall 33. At the end of 70 this first portion of its clockwise movement to-

ward its inoperative position, the basin unit 62 will assume a position somewhere between its solid line position shown in Fig. 4 and its broken line position shown at 62a, and then the lug 101 will be disposed at the right-hand extremity of slot 98. On continued clockwise rotation of the basin unit 62, lug 101 moves upwardly in slot 99, rotating about lug 100, now disposed at the right-hand extremity of slot 98, until lug 101 reaches the upper left-hand extremity of slot 99. At the end of this movement of lug 101, the basin unit 62 assumes the vertical, inoperative position shown at 62a in Fig. 4 against a pair of cushions 102 that are fixed at spaced points on wall 33. A locking latch 103 may be mounted at each end of the housing unit 70 for holding the basin unit in its lowered, inoperative position, and a second latch 104 may be provided at each end of the housing 70 to support the basin unit 62 in its raised operative position. The details of these latches 103 and 104 form no part of the present invention, as any conventional type latch of sufficient strength will serve satisfactorily.

Referring to Figs. 3 and 4, each washbasin 71, 72, or 73 is provided with a drain pipe, generally indicated at 109, that extends to a common drain header 110. This drain header 110 is disposed closely adjacent to wall 33, and is disposed throughout the length of the basin unit 62. This header 110 is supported in some suitable manner on end member 94 (see Fig. 3), and at the opposite end of the basin unit 62 the header 110 projects into the end member 95 and connects with a vertical riser 111 through a conventional trap 112.

The drain pipe 109 is connected to a basin drain member 108 projecting from the bottom of each of the washbasins 71, 72, and 73, and comprises a segment 113 connected by means of a ball joint 114 to the basin drain 108 and telescoping at its other end into an intermediate segment 115. A suitable packing gland 116 is provided to seal the telescoping joint. Intermediate segment 115 is connected by means of an elbow 117 (see Fig. 3) and a ball joint 118 to a longitudinally extending member 119, the latter in turn being directly connected to the header 110 through a second elbow 120 and connecting segment 121.

Each of the washbasins 71, 72, and 73 is provided with a cold and hot water faucet 122 and 123, respectively, which discharge into a common outlet 124 into its corresponding washbasin. Cold and hot water pipes 125 and 126, respectively, extend substantially throughout the length of the basin unit 62. The cold water pipe 125 is connected to the cold water faucet 122 through suitable piping indicated generally at 121, while the hot water pipe 126 is connected to the hot water faucet 123 by means of suitable piping 128. These cold and hot water pipes, with their connections to the faucets, are completely housed in housing member 70, as best shown in Fig. 4, and pass through the end wall 78 of the housing into the end member 94 by means of cut-out portions 129 provided both in the end wall 78 and in the adjacent wall of end member 94. The cold and hot water pipes 125 and 126, when they pass into the end member 94, are connected to suitable cold and hot water supply lines, indicated at 130 and 131, respectively, in Fig. 3, by means of flexible connections 132 and 133, respectively. Conventional valves 134 and 135 are disposed, respectively, in the hot and cold water supply lines.

Thus, as the basin unit 62 is rotated from its

operative position, shown in solid lines in Fig. 4, to its inoperative position shown in broken lines, each drain pipe 109 enters an opening 136 in the bottom wall 76 of housing 70. The piping is allowed to pivot where necessary by virtue of the various ball joints, such as shown at 114 and at 118, and the changes in length of each of the drain pipes 109 caused by the different pivot points for the basin unit 62 and the pipes are provided by the telescoping joint. The flexible connections 132 and 133 in the end member 94 allow for the movement of the cold and hot water pipes 125 and 126, respectively.

Referring now to Figs. 4, 6, 7, and 8, each of the chairs 63 is provided with framing that includes side members 140 and 141, providing suitable legs 142 and arm rests 143. A seat cushion 144 is supported on the frame in a conventional manner, and a back rest 145, normally disposed at an upright position shown, for example, in Fig. 8, is pivoted at 146 to the frame members 140 and 141 so that it may be rotated to an inoperative position shown in broken lines in Fig. 4, where it rests upon the seat cushion 144. When in use the back rest 145 assumes the upright position shown in Fig. 8, and in this instance the basin unit 62 is disposed in its vertical inoperative position against the wall 33. When the back rest 145 is collapsed to its inoperative position, as shown in Figs. 4 and 7, for example, the chair 63 fits beneath the basin unit 62 when the latter is in its horizontal operative position shown in Fig. 7.

Thus, as shown in Fig. 1, the lounge 32 may be in the form of an elongated single room with the chairs 63 in place for use, in which case the basin units 62 are in their inoperative positions disposed vertically against the aisle partition 33. In this condition a lounge with adequate seating capacity is provided for the convenience of the passengers normally occupying the seats 31 in the remainder of the coach, or the seats 60 and 63 may be sold separately to passengers that, for example, may be traveling during the night only or for only part of the day. The first thing in the morning, the partition 57 can be closed to divide the lounge 32 into two separate rooms 32a and 32b so as to divide the lounge into a men's room and a women's room. In this event the chairs 63 are not occupied and are moved to the center of the room and collapsed with their back rests against their respective seat cushions. The latches 103 are then moved out of the way of the basin unit 62, and the basin unit is raised to its horizontal operative position and supported in this position by manipulation of the latches 104 disposed at opposite ends of the basin unit. The chairs 63 are then placed beneath the basin unit, as shown in Fig. 7, and are thus placed out of the way of persons wishing to use the basin unit. The cover member 87 is unlocked and rotated to its open position shown in broken lines 87a in Fig. 4 and in solid lines in Fig. 7. The basin is thus made ready for use, and clean towels are accessible, as previously mentioned, through the slots 90 (see Fig. 6).

Doors 44 and 45 provide access to toilets 42 and 43 from the men's room 32a, and door 41 provides access to the toilet 39 in the women's room 32b. During these periods of the day or night, doors 49 and 46 may be locked so that access to toilets 39 and 42, respectively, may be had only from rooms 32b and 32a, respectively.

During the daytime, when it is desired to con-

vert the two rooms 32a and 32b into one lounge 32, the folding partition 57 may be opened so as to convert the two rooms into an elongated single room. The collapsed chairs 63 are now removed from beneath each of the basin units 62, and the basin units are moved to their inoperative position by first closing the cover member 87 and locking it, and then releasing the latches 104 to permit lowering of the basin unit 62 to its vertical position shown in broken lines 62a in Fig. 4, or in solid lines in Fig. 8. When the basin unit has been locked in this inoperative position by manipulation of the latches 103, the chairs 63 may be moved with their backs against the basin unit 62, as shown in Fig. 1, after first raising each back rest 145 to its operative position, as shown in Fig. 8. When lounge 32 has been thus converted for daytime use, doors 41, 44 and 45 may be locked so that only toilets 39 and 42 can be used, and doors 40 and 46 are unlocked so that access may be had only from the aisle 36.

As shown in Figs. 3 and 6, the end members 94 and 95 are each provided with a partition 149 that supports the forward portion shown at 150 from the remainder of the end member. This forward portion 150 of each end member 94 and 95 is hollow and serves as a soiled towel retainer, an opening 151 being provided in the front wall of each of the members, as shown in Fig. 6, through which the soiled towels may be deposited. A hinged door 152 will give access for removal of soiled towels from the towel retainer, and a second hinged door 153 provides access to the valves 134 and 135 in the end member 94.

Referring again to Fig. 6, a mirror 154 may be disposed on the aisle wall 33 behind the washbasins 71, 72, and 73, and an electrical outlet receptacle 155 is shown mounted on the wall directly above each of the washbasins.

Referring to Fig. 2 a second embodiment of the invention is shown wherein the lounge 32 is divided into the two smaller rooms 32a and 32b by means of a dividing wall in the form of a reinforced curtain 160 that is fastened at one end to the car side wall 27 as at 161 and projects across the lounge and is fastened at its opposite end to the aisle partition 33 at 162. Inner reinforcing ribs 163 give rigidity to the curtain. This curtain can be unfastened at 162 and pushed back against the car side wall 27 so as to open up the lounge into one room. The details of this curtain 160 per se, form no part of the present invention and therefore a diagrammatic showing only is made herein.

In this embodiment of the invention the lounge 32 is shown disposed intermediate the ends of the car, there being passenger space adjacent to both ends of the lounge. As shown in Fig. 2, the doors indicated at 55a and 56a are disposed at opposite ends of the lounge instead of adjacent to the center of the aisle wall 33 as in the case of the embodiment disclosed in Fig. 1. Thus in this second embodiment of the invention the combination seat and basin units shown at 164 are arranged closely adjacent to each other, there being provided only sufficient room therebetween for the curtain 160 to extend to the aisle partition 33. In this embodiment of the invention a second toilet 165 may be provided adjacent to room 32b in addition to the single toilet 39 that was provided in connection with the first embodiment of the invention. Thus in Fig. 2, the two toilets are shown adjacent to the end of each of rooms 32a and 32b.

In Fig. 2, each of the toilets 39 and 42 is

shown as being equipped with a toilet unit 166 having a hopper generally indicated at 167 and a folding wash basin 168.

Each of the units 164 shown in Fig. 2 is a combination sofa and wash basin. In room 32a of Fig. 2 the unit is shown in position where the sofa may be utilized, whereas in room 32b the basins are disposed in their operative position and the sofa is inaccessible.

Referring now to Figs. 9 to 15 inclusive the combination sofa and basin unit 164 comprises generally a sofa seat portion 169, a back rest, basin unit generally indicated at 170 and a pair of spaced upright end members diagrammatically shown in Fig. 2 at 171 and 172.

Referring now to Fig. 9 the sofa seat 169 may comprise a seat frame generally indicated at 173 which may be carried by the end members 171 and 172 and upon which may be mounted three or more seat cushions 174.

Adjacent to the back edge 175 of the seat cushions 174 is the combination back rest, basin unit 170 that is normally disposed in an upright position shown in solid lines in Fig. 9 during the time unit 164 is being used as a sofa. The forward face of the back rest, basin unit 170 may be cushioned at 176 with rubber or like cushioning material and upholstered in any well known manner. In the opposite face of the back rest, basin unit 170 is mounted a plurality of wash basins 177 and these basins are contained within the back rest, basin unit 170 and are accessible through the rear face of the unit 170. The construction of the basin unit can be similar to that disclosed in detail in connection with the first embodiment of the invention and shown in Fig. 4. In this second embodiment of the invention, however, no cover member is provided because when the back rest, basin unit 170 is in its upright position shown in solid lines in Fig. 9 it is disposed wth the basins 177 against the aisle partition 33.

Adjacent to the opposite ends of the back rest, basin unit 170 is a supporting rod 180 that is pivotally mounted adjacent to its lower end to the wall of the adjacent end member 171 or 172 as the case may be. This pivot connection is shown for example in Fig. 10 at 181. The opposite end of the supporting rod 180 is pivotally mounted as at 182 to the end wall of the back rest, basin unit 170. In Fig. 10 the back rest, basin unit 170 is indicated in its upright position corresponding to that shown in solid lines in Fig. 9. Referring to the broken line position of the back rest, basin unit 170 indicated for example at 170a in Fig. 9, it is noted that the upper pivot connection 182 is made substantially midway between the forward and rear edge of the back rest, basin unit 170a. This connection is so disposed with respect to the back rest, basin unit 170 that the supporting arms 180 at each end of the back rest, basin unit 170 can support the weight of the back rest, basin unit 170.

Again referring to Figs. 9 and 10 a pair of guide bars 183 and 184 are mounted adjacent to each end of the back rest, basin unit 170 on the wall of the adjacent end member 171 and 172. These guide bars 183 and 184 extend vertically and parallel and are spaced to provide therebetween a track portion indicated in Fig. 10 at 185. A lug 186 is mounted on each end wall of the back rest, basin unit 170 and projects outwardly therefrom so as to enter the corresponding track portion 185. This lug 186 is disposed adjacent to the rear edge of the back rest, basin

unit 170 and is adapted to move vertically in its corresponding track portion 185 as will be presently described.

A plurality of rubber bumpers, one of which is shown at 187 in Fig. 9 may be provided on the base frame portion 173 of the sofa seat 169 to support the back rest, basin unit 170 when it is in its upright position shown in solid lines in Fig. 9.

A suitable lock generally indicated at 188 in Fig. 9 may be mounted in the forward edge of the back rest, basin unit 170 and may be adapted to cooperate with a stop member 189 mounted in the adjacent end member 171 or 172. A corresponding stop member 190 may be located adjacent to the front edge of each of the end members 171 and 172 to cooperate with the locking mechanism indicated at 188a when the back rest, basin unit 170 is in its horizontal position shown at 170a in Fig. 9.

Referring to Figs. 11 to 15 inclusive this locking mechanism may include a pair of oppositely disposed locking arms 200 and 201 mounted on the back rest, basin unit 170 which are pivotally mounted at one end thereof as at 202 and 203 respectively to a rocking member 204. This rocking member 204 in turn is pivoted at 205 to a bracket 206 carried by the back rest, basin unit 170. A suitable handle shown at 207 in Fig. 12 may be provided to manipulate the rocker member 204. At the opposite end of each of the arms 200 and 201 are housings generally indicated at 208 in which are slidably mounted bolts 209. These bolts 209 are backed by compression springs 210 that normally urge the bolts 209 outwardly. Each of these housings 208 is mounted adjacent to one of the end walls of the back rest, basin unit 170 so that each bolt 209 projects normally beyond the plane of the corresponding end wall. The handle 207 may be rotated so as to turn the rocker member 204 (Fig. 11) in a clockwise direction thereby drawing the bolts 209 at the opposite ends of the back rest, basin unit 170 into their respective housing 208 thereby positioning each bolt 209 so that its free end is retracted at least to the plane of the corresponding end wall of the back rest, basin unit 170.

Each of the stops 189 and 190 (Figs. 9 and 15) is provided with a shoulder 211 which cooperates with the corresponding bolt 209 of the locking mechanism to hold the back rest, basin unit 170 in its upright position (in the case of stop 189) or in its horizontal position (in the case of stop 190).

Piping to the basins 177 is contained primarily within the hollow interior of the back rest, basin unit 170 and is connected with the vertical risers 130 and 131 (Fig. 9) by flexible connections in the manner previously described with respect to the first embodiment of the invention. These risers 130 and 131 are contained in the end members 171 and 172 as previously described.

In operating the back rest, basin unit 170 the normal position wherein the combination sofa and basin unit 164 is utilized as a sofa is shown in Fig. 2 (room 32a) and Fig. 9. In this position the back rest, basin unit 170 is disposed substantially vertically with the wash basins 177 substantially against the aisle partition 33. Thus the cushion 176 is exposed for use as a back rest. To move the back rest, basin unit 170 to the horizontal position shown in broken lines 170a in Fig. 9, the car attendant first unlocks the back rest, basin unit 170 by manipulation of the handle 207, as previously described with

respect to Figs. 10 to 15 inclusive, and then pulls the basin forward from a position directly in front of the sofa seats 169. By thus pulling the back rest, basin unit 170 forward it is raised and rotated by virtue of the movement of the supporting arm 180 from its rearwardly sloping position, shown in Fig. 9 to its upright position. During this movement of the back rest, basin unit 170 the lugs 186 are raised vertically in their respective tracks 185 between the spaced guide bars 183 and 184 until the lugs reach the top of their respective tracks. The guide stop 212 serves as an upper support against which the lugs 186 may rest. The back rest, basin unit 170 at this time has assumed the position shown in Fig. 9 at 170a and is locked in this position by cooperation of the locking mechanism with the stops 190. To return the back rest, basin unit 170 to its upright solid line position shown in Fig. 9, the operation is reversed.

In this second embodiment of the invention a used razor blade receptacle may be supplied at 213 in each of the end members 171 and 172. A towel cabinet 214 may be provided on the aisle partition 33 over each of the basins 177 and these towel cabinets 214 may be so situated that when the back rest, basin unit 170 is in its upright position, each towel cabinet 214 will be disposed within a corresponding basin 177 as shown in Fig. 9. A mirror may be provided on the aisle partition as previously described with respect to the first embodiment of the invention.

A number of embodiments of the invention have thus been described.

It is apparent that these embodiments provide during most of the twenty-four hour day period maximum seating facilities in a railroad car.

There are a great many trains operating over schedules which call for departure of the train in the afternoon or early evening and arrival at the final destination the following morning. Conventional coaches of the deluxe type should carry enough washing and toilet facilities to accommodate during early morning hours the entire group of passengers arriving to the final destination. All of this space is not generally used and therefore is not required from the time of departure of the train until the morning hours. The present invention makes it possible to utilize this space during the time when it is not utilized for washing and toilet purposes. This has a very decided advantage because on all trips there are certain passengers who may board the train at the initial station or at stations along the right-of-way but who wish to leave the train early in the evening or during the nighttime at a wayside station. By providing an arrangement of the type described, these passengers cannot be accommodated without providing additional cars. It is also possible by virtue of the present invention to provide a single lounge or smoking space for both men and women without the need of an additional lounge car.

It may be desirable to make certain changes in the embodiments shown. For example: the folding partition shown in Fig. 1 may be mounted on the car side wall 27 instead of on the aisle wall 33. In this event, when the partition is in its open position it will be disposed behind one of the chairs 60. Such an arrangement would make it possible to utilize both doors 55 and 56 to provide access to and from the large single lounge. It may be found desirable to provide additional seating capacity in the lounge during the time the movable wall or partition 57 is in its

open position. This can be accomplished by providing a folding chair which may be placed at each end of the lounge adjacent to walls 34 and 35 respectively. This is possible because during the time the seating capacity is required the doors leading from the lounge into the various toilets are closed and locked and these extra seats may be disposed in front of these doors. When these extra chairs are not needed they can be folded up and placed against the partition, which, in that event, divides the lounge into separate rooms 32a and 32b.

I claim:

1. A room bounded by four fixed walls, a movable wall adapted to divide the room into two smaller rooms, seats in each smaller room aligned along one of the fixed walls, an elongated horizontally disposed basin unit over at least some of said seats in each room comprising a plurality of basins, the seats being disposed underneath the basin unit, and mounting means for the basin unit whereby the unit may be moved to an inoperative, upright position adjacent to the last mentioned seats to thereby make the seats accessible.

2. A room bounded by four fixed walls, a movable wall mounted on one fixed wall and extendable across the room to the opposite fixed wall so as to divide the room into two smaller rooms, seats in each smaller room aligned along one of the fixed walls, an elongated horizontally disposed basin unit over at least some of said seats in each room comprising a plurality of basins, the seats being disposed underneath the basin unit, and mounting means for the basin unit whereby the unit may be moved to an inoperative, upright position adjacent to the last mentioned seats so as to make the seats accessible.

3. A room bounded by four fixed walls, a movable wall mounted on one fixed wall and extendable across the room to the opposite fixed wall so as to divide the room into two smaller rooms, a doorway in one of the fixed walls on each side of the partition providing access into the rooms, seats in each smaller room aligned along one of the fixed walls, an elongated horizontally fixed basin unit over at least some of said fixed seats in each room and comprising a plurality of basins, the seats being disposed underneath the basin unit, and mounting means for the basin

unit whereby the unit may be moved to an inoperative, upright position adjacent to the last mentioned seats to make the seats accessible.

4. In a railway car having an aisle extending lengthwise thereof, an elongated room serving as a lounge with seats therein but being convertible into two separate rooms with washbasin facilities in each room, said elongated room being formed by an outside car wall, an aisle wall, and two spaced apart transverse end walls, a movable partition disposed substantially midway between the end walls and adapted to extend from the outside wall to the aisle wall so as to divide the elongated room into two smaller rooms, the movable partition being fastened to one of the last two mentioned walls, extendable from said wall to the other wall, and being removably fastened to the other so as to optionally divide the elongated room into two separate rooms, a doorway in the aisle partition on each side of the folding partition, an elongated horizontally disposed basin unit on each side of the movable partition pivotally secured to the aisle wall, each basin unit comprising an elongated housing, a plurality of basins arranged side by side in the housing, the housing being adapted to pivot from a horizontal operative position to a vertical inoperative position, and seating means disposed underneath the basin unit when the latter is in its operative position and being accessible when the basin unit is disposed in its inoperative position.

JAMES E. CANDLIN, JR.
